UNITED STATES PATENT OFFICE.

LOREN M. DARLING, OF DES MOINES, IOWA.

DESIGN FOR A RING OR SIMILAR ARTICLE.

50,808.

Specification for Design.

Patented May 22, 1917.

Application filed January 6, 1917. Serial No. 141,038. Term of patent 14 years.

To all whom it may concern:

Be it known that I, LOREN M. DARLING, a citizen of the United States, and resident of Des Moines, in the county of Polk and State of Iowa, have invented a new, original, and ornamental Design for a Ring or Similar Article, of which the following is a specification, reference being had to the accompanying drawing, forming part thereof.

Figure 1 shows a plan view of a ring embodying my invention.

Fig. 2 shows a side elevation of the same, the lower portion of the ring being broken away, and

Fig. 3 is a side elevation taken from the opposite direction from the view taken in Fig. 2.

I claim:

The ornamental design for a ring or similar article, as shown.

Des Moines, Iowa, December 29, 1916.

LOREN M. DARLING.
